ATTORNEY

UNITED STATES PATENT OFFICE.

WILLIAM L. TROUP AND JOHN A. C. GERMER, OF HARRISBURG, PA.

CAR-AXLE BOX.

SPECIFICATION forming part of Letters Patent No. 257,109, dated April 25, 1882.

Application filed November 23, 1881. (No model.)

To all whom it may concern:

Be it known that we, WILLIAM L. TROUP and JOHN A. C. GERMER, both of Harrisburg, county of Dauphin, and State of Pennsylvania, have invented a new and useful Improvement 5 on Car-Axle Boxes, the same being an improvement on our invention under the same subject patented August 9, 1881, and numbered 245,586, of which first-named invention the following is a specification.

Our present invention has for its object, first, to construct and arrange the pillow-block which closes the top of the casing or box and the ledges or offsets at said opening in such 15 manner that only a small amount of jacking of the truck will be necessary to disengage the interlocked parts on said block and at said opening; second, hinging the spring door or lid of the casing to the removable pillow-piece 20 that broken doors or hinges may be replaced at less cost and trouble than where the door-knuckles are made part of the casing; third, providing the under side of the removable pillow-block with a shouldered longitudinal seat, 25 in which the top of the journal-box is admitted and guided against canting by the side action of the car-axle when the brake-liner acts on the wheel. We attain these objects by the construction and arrangement of parts as illustrated 30 in the accompanying drawings, in which—

Figure 1 is a cross-sectional view of the casing and of the parts therein, the same being taken at the indicated line W, Fig. 2. Fig. 2 is a longitudinal vertical section of our invention. Fig. 3 is a perspective view of the pillow-block with the door or casing-lid attached thereto. Fig. 4 is a cross-sectional view of the pillow-block, journal-box, and axle, superimposed in the order recited.

Similar letters refer to similar parts throughout the several views.

We aim by our present improvement not only to remove a damaged journal-box more easily than heretofore by removing the top of 45 the casing or the pillow-block to make said box more accessible, but we specially construct and arrange the parts that said pillow-block can be removed by as little jacking as possible, about five-eighths of an inch elevation of the truck-

frame being sufficient for said purpose. This 50 result is attained by locating the detents of said block quite up in the bevel and step-form edges of the casing's top opening, and by making said detents and the notches for them in said block shallow vertically.

Referring to the above-mentioned drawings, A A denote the walls of the casing; l z, its bottom and front. t t are bolts holding the truck-bars T T' S thereon; and B denotes the rear end of the top of the casing, the only part of 60 top cast shut.

F denotes the removable pillow-block, having in its side edges the step-form recesses m n, into which corresponding lugs, m' n', in the casing-opening, near its top, apply as detents 65 to hold said block against displacement until the truck is jacked up to a little more than the height of the recesses m n.

P P denote ledges or guides on the under side of said pillow-block, forming a seat between them, into which the top of the journal-box G applies, and by which it is steadied on the axle M against lateral canting, as described.

K denotes a partition in the casing, whose 75 top K' is by our arrangement for jacking capable of being higher than usual, thus affording a deeper chamber for the stuffing and the lubricant. The collar-recess K² is made in the usual way to exclude dust from the casing.

The door or lid Q is hinged at knuckles L O to the pillow-block F, as shown, a spring, b, being combined therewith in the usual manner. The chief advantage of this construction is this: The door or the pillow-block, if broken, 85 can be replaced at less cost and delay than the casing, the door and its hinge being the parts most liable to break.

For securing by Letters Patent of the United States what we deem new and useful, we 90 claim—

1. The pillow-piece F, provided with spring-hinge knuckles L or O, in combination with the spring-door Q, hinged thereto and removable therewith from the casing and repairable 95 distinct from the casing A A, as and for the purpose set forth.

2. The guiding-ledges P P, arranged longi-

tudinally on the under side of the pillow F, in combination with the brass or journal box G, admitted at its top between said ledges to resist the displacing side action of the brake, 5 and that said box may be freed of said ledges to facilitate its removal after said pillow-piece has been removed, substantially as set forth.

In testimony that we claim the foregoing as

our invention we have hereunto set our hands and seals.

WILLIAM L. TROUP. [L. S.]
JOHN A. C. GERMER. [L. S.]

Attest:

THEOPHILUS WEAVER,
PETER STUCKER.
